UNITED STATES PATENT OFFICE.

THEODORE E. BARKER AND ALFRED E. ELLEFSEN, OF DENVER, COLORADO, ASSIGNORS
TO THE DENVER ROCK DRILL MANUFACTURING COMPANY, OF DENVER, COLORADO,
A CORPORATION OF DELAWARE.

CAGE ROLLER BEARING.

Application filed January 26, 1922. Serial No. 531,905.

To all whom it may concern:

Be it known that we, THEODORE E. BARKER and ALFRED E. ELLEFSEN, citizens of the United States, residing at Denver, in the county of Denver and State of Colorado, have invented certain new and useful Improvements in Cage Roller Bearings, of which the following is a specification.

The present invention has for its object the provision of an exceedingly simple and yet effective holder for roller bearings.

In the accompanying drawings:

Figure 1 is a side elevation of the preferred embodiment of the invention.

Figure 2 is a sectional view on the line 2—2 of Figure 1.

Figure 3 is an end elevation with the retaining ring removed.

Figure 4 is an end elevation of the retaining ring.

Figure 5 is a sectional view on the line 5—5 of Figure 2.

Figure 6 is a detail sectional view on the line 6—6 of Figure 4.

In the structure disclosed, a unitary body is employed, consisting of a head ring 7, from one side of which projects partition walls 8 having concave opposite faces, forming pockets 9. In these pockets are placed the usual roller bearings 10. In the preferred form of construction the body is formed from a cylinder, the pockets 9 being drilled out.

The free ends of the partition walls 8 are provided with recesses 11 forming in effect the sections of a circle, as will be clear by reference to Figure 3. A retaining ring 12 is adapted to fit upon this end of the body, and consists of heads 13 that close the open outer ends of the pockets 9, these heads being connected by integral webs 14. The webs 14, as shown particularly in Figure 6 are tapered or generally dovetailed, and are of a size to fit in the recesses 11, the narrower sides being outermost. The end portions of the partitions 8 on opposite sides of the recesses 11 are then inset as shown in Figure 5, thereby securely holding the retaining ring in place.

From the foregoing, it is thought that the construction, operation and many advan-

tages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described our invention, what we claim as new, and desire to secure by Letters Patent, is:

1. A cage for anti-friction roller bearings comprising a body having a plurality of separating walls defining a series of open ended pockets for the bearing elements, said walls being connected at one end, and a retaining ring at the free ends of the walls and having enlarged heads that substantially close the open ends of the pockets and means embracing the portions of the ring between the heads for securing said ring to the said walls.

2. A cage for anti-friction roller bearings comprising a body having a plurality of separating walls defining a series of open ended pockets for the bearing elements, the free ends of said walls being recessed, and a retaining device bridging the open ends of the pockets and having outwardly tapered portions in the recesses of the partition walls, the end portions of said walls on opposite sides of the recess being upset over said portions.

3. A cage comprising a single-pieced body comprising a ring and a plurality of partition walls integral therewith and projecting from one side of said ring, providing a series of open ended pockets for the bearing elements, the free ends of said walls having recesses, and a retaining ring comprising a plurality of closure heads for the open ends of the pockets and tapered portions that are in the recesses of the walls, said walls being upset over the said portions.

In testimony whereof, we affix our signatures in the presence of two witnesses.

THEODORE E. BARKER.

ALFRED E. ELLEFSEN.

Witnesses:

S. C. SANDERSON,
H. E. FISKE.
